UNITED STATES PATENT OFFICE.

JOSEPH E. CRISP, OF SOMERVILLE, GEORGE W. COPELAND, OF MALDEN, AND THOMAS BARRETT, OF BOSTON, MASSACHUSETTS, ASSIGNEES, BY MESNE ASSIGNMENTS, TO THE BOSTON LASTING MACHINE COMPANY, OF PORTLAND, MAINE.

TACK-DRIVING MACHINE.

SPECIFICATION forming part of Letters Patent No. 505,031, dated September 12, 1893.

Application filed July 31, 1891. Serial No. 401,286. (No model.)

To all whom it may concern:

Be it known that we, JOSEPH E. CRISP, of Somerville, and GEORGE W. COPELAND, of Malden, in the county of Middlesex, and THOMAS BARRETT, of Boston, county of Suffolk, State of Massachusetts, citizens of the United States, have invented new and useful Improvements in Suspended-Power Tack-Drivers, of which the following is a full, clear, and exact description, reference being had to the accompanying drawings, forming a part of this specification.

The invention relates to improvements in automatic machines for arranging, selecting and driving tacks, loosely placed in a receptacle attached thereto.

The objects of said improvements are to enable the operator to drive tacks in rapid succession, one after the other, and at any desired place or angle within the field of action of the machine, without the rebound common to suspended power operated machines of this class; and this is accomplished by suspending and balancing the machine in the manner herein set forth and by causing the automatic mechanism, which lifts the driver, to raise it, then disconnect from and leave it locked against the tension of the driving spring, while the machine is being moved from point to point, whereby the tack can be driven immediately and in the shortest period of time possible after the operator has pressed the discharging trigger of the machine.

The invention consists in mechanism for accomplishing these objects hereinafter described and illustrated in the drawings.

It also consists of novel feeding mechanism to insure perfect driving whereby the tacks are kept loose in the lower end of the chute or roadway; and are selected therefrom singly, with great precision, then positively and suitably fed into the throat of the machine and there held until the hammer or driver nearly reaches the tack.

It also consists in a constantly revolving elevator wheel, by means of which the chute or roadway will be supplied with sufficient tacks, during the periods of rest of the driv-

ing mechanism, to fill all demands for tacks that may be required during the periods of driving, when the machine is held at such angles that no tacks can be delivered to the receiving part of the chute or roadway.

Figure 1, is a side elevation of the suspended and balanced machine, with the driving pulley removed to show the manner of hanging it on the counter-balanced arm. Fig. 2, is a side elevation, showing enlarged, the same side as Fig. 1, part of the driving pulley and part of the suspending arm dotted in. Fig. 3, is a side elevation opposite to that of Fig. 2, showing by dotted lines, the relations to each other of receptacle for tacks, elevator wheel and roadway, by which the tacks are brought to the feeding device. Fig. 4, is a plan of the machine showing in section a portion of the suspending arm. Fig. 5, is a vertical cross section on line *w w*, Fig. 2. Fig. 6, is a horizontal cross section of Fig. 7, on line *x x* with cover and elevator wheel in position. Fig. 7, is a side elevation of the receptacle for loose tacks, with the cover and elevator wheel removed. Figs. 8 and 9 are cross sections on line *y y*, Fig. 2, showing the relations and operation of the tack feeding mechanism. Figs. 10, 11, are cross sections on line *z z* Fig. 2, showing the automatic operation of the roll which raises and leaves the driver ready for action. Fig. 12, is an elevation of the elevator wheel which revolves close to the tack chute or roadway. Fig. 1, shows substantially the ordinary method of suspending and balancing machines of this class, where the operating power is taken from an overhead shaft.

The improvement therein, consists in forming the straight part of the horizontal counter balance arm round, and fitting it, so that it will slide and turn freely in the sleeve *A'* using the spring *A²*, to maintain the tension of the belt *A³*, as the machine is twisted angularly to the right or left and in making the counter balance *A⁴*, eccentric with sufficient preponderance of weight below, so that upon the release of the machine the counter balance will cause it to automatically return to a vertical position of rest.

At the outer end of the counter balance arm, is a bearing A⁵, into which the driving machine is hung, so that it can be rocked forward and backward as desired, the joints and counter balanced arm allowing the nozzle, a horizontal range of about twelve by twenty four inches and a vertical range of about twelve inches and the tacks may be driven at any angle less than thirty degrees from the vertical position of rest.

The frame of the machine consists of the central web B, merging into the round handle B⁸, through the center of which the driving bar F³, reciprocates, and to the two sides of this frame are attached the operating parts of the machine. A boss B', Fig. 2, is so located upon the web B, that when its outside is fitted to and hung in the counter balanced arm at A⁵, the driver will stand about vertical when the machine hangs free, and through the center of this boss B', is formed the bearing for the constantly revolving main shaft C.

The frame B, forms one side of the tack receptacle B³, and leading from this receptacle to the feeding devices is the inclined chute or roadway B⁴, in which the tacks are arranged and led.

The cover B⁵, of the tack receptacle has a bearing formed in its center for the shaft D, and fixed to the inner end of this shaft is the elevator wheel D' the inner side of which when the cover B⁵, is secured in position by the screws B⁶, contacts with the roadway B⁴, its cover B⁷, and all that part of the side of the receptacle below the roadway, for the purpose of preventing the tacks from wedging the wheel D' as it revolves among them. The tacks move into the buckets of the elevator wheel near the bottom and opposite the side next the roadway, and are delivered over the upper end of the roadway at B⁸, where the frame is inclined backward to insure freedom.

Figs. 3, 6, 7, show the relations of elevator and roadway.

The elevator D' receives constant motion from the main shaft C by the eccentric C' reciprocating the hooked pawl C², over the teeth of the ratchet wheel D², fitted to the shaft D, the retainer pawl D⁴, and spring D⁵, insuring revolution of the ratchet wheel.

Between the upper end of the roadway B⁸, and the upper end of the cap B⁷, the top of the roadway is beveled as at B⁹, to cause the tacks that have not started correctly, to fall off, and again be elevated, the tacks which fall over the side next the elevator passing back through the center thereof and those falling over the opposite side passing around the roadway through the passage B¹⁰, and thence through the center of the elevator wheel. The above construction, causes most of the tacks to pass correctly under the retaining cap B⁷, of the roadway on their journey to the feeding devices, but some of the tacks will fall from the elevator buckets in correct line with the path of the roadway with their points resting upon the head of a correctly positioned

tack, preceding them and so ride down to the cap where the point passing under said cap will act as a wedge to block the flow of succeeding tacks. To remove such obstructions and preserve the continuity of flow, down the roadway, a picker is constructed as follows: Pivoted to the frame B at B'', in proper relation to the upper end of the cap, 75 is the swinging arm E, Figs. 2, 6, and 7, whose spring E', tends to swing it toward the upper end of the roadway, and fitted to this swinging arm is the spring picker E², whose swinging end is fitted to catch any tack which may have wedged itself and move it so far away from the upper end of the cap B⁷, that said tack will fall one side or the other of the chute or roadway. Automatic motion is given to the swinging arm E, by the extension E³, 85 which carries the curved arm E⁴, so that its end will engage with the pins D⁸, fixed in the face of the constantly revolving ratchet wheel D², which pins press back and then release the arm E⁴, and the spring E' gives the 90 picker point the desired motion.

It is understood that in a machine with the angular range given the one herein described, there are certain angles of operation, during which no tacks can be delivered into the 95 chute or roadway and that at such times, the available supply will rapidly decrease; but the length of the chute is made sufficient to tide over periods of want and when the machine is not in active operation driving tacks, 100 the constantly running elevator will again fill the chute or roadway ready for another call.

The tack driving mechanism is constructed and operated as follows: A swinging arm F, is hung upon an extension of the frame B, at 105 F', and a link F², connects the opposite end of this swinging arm to the driver F³, which is reciprocated and guided in the handle B², by these connections. To raise the driver, a proper bearing F⁴, is formed upon the swinging arm F, and to this bearing is fitted the elevating roll F⁵, Figs. 3, 10, and 11, so that it can revolve; and also slide endwise to the positions shown by Figs 10 and 11. Affixed to and forming part of the constantly revolving main shaft C, is the curved lifter C⁴, which revolves upon the same side of the frame B to which the arm F, is attached; and whose path of revolution will cause it to engage with the roll F⁵, and raise the swinging arm F, when the roll F⁵, is in the position shown by Fig. 10 and when the swinging arm is locked up, the wedge C⁵, forming the outer end of the lifter C⁴ ships the roll F⁵, to the position shown by Fig. 11, so that the roll can swing with the 110 arm F, down past the lifter, no matter what its angular position, whenever it is desired to drive a tack. After the driver has descended to its full limit a shipper spring C⁶, ships the roll F⁵, back to the position shown by Fig. 10, 115 and the lifter will again raise the arm F. To insure the roll F⁵, always clearing the lifter C⁴, during its downward motion, a groove is formed therein as shown by Fig. 10, and a

guide C⁷, is mounted on a swinging guide-arm C⁸, which prevents the shipperspring C⁶, from acting, only when the roll F⁵, is at its lowest point; and in case the shipper spring C⁶, does not move the roll F⁵, completely clear of the guide C⁷, the guide-arm spring C⁹, gives, and allows free ascent of the roll F⁵. The active or downward motion of the driver is produced by the spring F⁸, connected to the 10 swinging arm at F⁷, and the frame at F⁹.

The driving bar is held up against the spring F⁸, and released when it is desired to drive a tack as follows, (see Figs. 2, 3, 4, 5:) Fixed to the swinging arm F, is a block F⁶, 15 and pivoted in a bearing formed through the frame B, is the swinging dog G, whose stop pin G' allows it to swing a little under the block F⁶, and hold the swinging arm F up as desired; to move this dog G, from under the 20 block F⁶, and allow the driver to descend there is pivoted in another similar bearing below that for the dog G, the trigger G², which is formed in one piece with its pivot pin G⁷ and pivoted to the upper end of this trigger 25 is the sear G³, the spring of which, G⁴, presses it up, toward the lower end of the dog G (see Fig. 3) and by Fig. 2, it will be seen that through the pivots of G and G², are pins G⁵, G⁶, which hold these parts in place and these 30 pins are prolonged toward the rear of the machine and connected at their outer ends by the spring G⁶, which spring and pins draw the dog and trigger into operative positions. The sear is so fitted on the trigger that when 35 the trigger is pressed fully back, the sear passes under the arc of motion of the lower end of the dog and thus allows the dog G, to catch under the block F⁶, as soon the block F⁶, is in a position to do so; and the sear 40 spring G⁴, yields, when the trigger G², is released, so that the spring G⁷, can draw the trigger back for another active motion. The driving bar F⁸, terminates in the driver F¹⁰, and below the handle B², is fixed a guide 45 H, to align the lower end of the driver F¹⁰. Below this guide is the throat H' into which the tacks are delivered by the feeding finger M'; this throat is made in two parts, the front having a slot for the feeding finger to reciprocate in; and below this throat is the nozzle or driveway H², through which the tacks are driven. Through the inner part of the throat H' and also the frame B, are fitted the yielding blocks K, Figs. 8, 9, which form part of 50 the throat and also serve as inclined gates, to prevent the tacks from flowing from the roadway into the throat. These gates K, are pressed across the roadway by the springs K', which springs are held in position by the 55 screw K², Fig. 3; and the upper plane of these gates coincides with that of the lower end of the roadway, so that the tacks as they reach the gates will pass over and rest upon and against them. The line of separation of 60 the gates K, is the lower edge of the slot formed in the front part of the throat for the feeding finger and so much of the upper gate

is removed that the feeding finger can be reciprocated without causing motion to either of them, unless it is carrying a tack from the 70 roadway to the throat, when the combined action of the two gates causes the tack to move squarely forward regardless of length or taper of shank, and as soon as the tack has entered the throat, the gates close behind it 75 and prevent its displacement under the action of the driver. The feeding finger M', is quite thin and separates and carries the tacks from the lower end of the roadway through the gates K, to the throat, and there holds 80 them until the driver nearly reaches their heads, when it commences to move back in a straight line, as in the common scratch feed, until it about reaches the rear of the inclined gates, of course, moving the tacks a 85 little back, during the last part of its motion; when it has reached this point, it commences to swing out from the tack chute until it reaches the extreme backward limit of motion and this swinging out allows the tacks to fall 90 and rest over and against the inclined sides of the gates K, as hereinbefore described. The return or feeding motion of the feeding finger is the same as that of the square or four motion feed; it moves behind the first 95 tack on the lower end of the roadway, then pushes it into the throat and there holds it, until it is desired to drive another tack.

The feeding finger M' has the preceding motions given to it, by the following mechanism: Projecting from the side of the frame B, shown by Fig. 2, is a bearing L, for the rock shaft L', the lower end of which terminates in the rocker arm L², and pivoted to and below L², at L³, is the bell crank lever M, 100 Figs. 2, 5, 8, 9, whose longer arm, during a portion of its motion, rides upon the outer side of the throat H' and to this end of the bell crank lever, the feeding finger M' is secured by the binding screw M², so that its point 105 will not rub over the back side of either roadway or throat as it reciprocates. A spring M¹, connected to this arm of the bell crank lever and to the arm L², draws the point of the feeding finger M' toward the roadway; 110 the opposite and shorter arm, is slotted at M³, and one side of this slot engages with the pin L⁴, fixed under the center of the rock shaft L, when the feeding finger has been drawn back to about the rear of the inclined gates 115 K, and causes the remainder of the backward motion of the rock shaft to swing the finger M' outward.

Motion is given to the rocker shaft L', by the adjustable arm L⁷, secured to its upper 120 end in the following manner: Fitted to slide in a slot N, formed through the frame B, is the incline or wedge N', Fig. 5, and a connecting rod N², connected to the swinging arm F, at F⁷, opposite the driving spring F⁸, gives 125 coincident reciprocation to the incline N'. Fixed to a collar forming part of the rock shaft is the pin L⁵, to which is connected the spring L⁶, which spring at all times draws the 130

rock shaft back with reference to the feeding finger M' and holds the swinging block L⁸, mounted under the outer end of the adjustable rock arm L⁷, in contact with the incline 5 N', the incline N', being so formed with reference to the feeding finger M' and the driver F¹⁰, that a tack is positively fed forward and held up, under the driver F¹⁰, until it commences its downward motion, when the feeding finger M', will move back for another tack.

What we claim, and desire to secure by Letters Patent, is—

1. In a machine for driving tacks, a constantly revolving lifter, a driving spring, a 15 driver disconnected from its raising mechanism, in combination with a swinging spring operated dog for locking said driver against the tension of the driving spring, substantially as shown and described.

2. In a machine for driving tacks, a constantly revolving lifter, in combination with a driver and endwise reciprocating roll for raising said driver, and mechanism substantially as described, to reciprocate said roll at 25 the termination of the movements of said driver, all constructed and operating substantially in the manner shown and described and for the purposes set forth.

3. In a machine for driving tacks, a feeding 30 finger and mechanism substantially as described for carrying it, mounted on the frame of the machine, intermediate mechanism connected to the driver elevating arm, operating a reciprocating cam, which actuates said feed finger carrying mechanism in unison 35 with the driver and holds the feed finger at its extreme forward position, when said driver is locked up, in combination with an interposed spring operated dog for holding the driver up, and an independent trigger and gear for releasing the driver and driving the nail or tack held by the feeding finger, all operating substantially as shown and described.

4. In a machine for driving tacks, the combination of the elevator wheel D' mounted 45 upon an axis at right angles to the direction of the chute or roadway B⁴, with the ratchet wheel D², hooked pawl C² and the eccentric C', substantially as shown and described.

5. In a machine for driving tacks, the combination of the chute or roadway B⁴, the picker E², mounted upon the swinging arm E, and operated by the pins D³, of the ratchet wheel D² acting upon the curved arm E⁴ ar-

ranged and operating substantially as shown 55 and described.

6. In a machine for driving tacks, the combination of the feeding finger M' mounted upon the bell crank lever M, provided with a slot M³, with the rocker arm L², and the spring 60 M⁴ substantially as described, whereby the feeding finger is caused to move back until it loosens the tacks in the lower end of the roadway and then passes around behind the first one of them and pushes it into the throat 65 of the driveway, and there holds it, until the driver is released.

7. In a machine for driving tacks, the combination of the feeding finger M', means substantially as described for actuating said finger, two independent gates K, which close the end of the chute or roadway B⁴, substantially as shown and described.

8. In a suspended oscillating tack-driving machine, the combination of the counter balanced arm A, sliding and revolving in the sleeve A', of the suspended mechanism, and the bearing A, upon one end of said arm A, and the eccentric counter balance A, on the other end, substantially as and for the purposes shown and described.

9. In a machine for driving tacks, a constantly revolving main shaft with a cam or lifter for automatically raising the driver attached thereto, an interposed swinging spring operated dog for holding said driver up, in combination with the trigger G² whereby the operator can at will set in operation the tack driving and feeding mechanism substantially as shown and described.

10. In a machine for driving tacks suitable for tack driving and feeding mechanism a constantly revolving main shaft operating an elevator wheel, in combination with cam or lifter for the driver a dog for holding the driver locked up against the tension of the driving spring and a trigger and sear for releasing said driver whereby the operator can at will set in motion the driving and feeding mechanism, substantially as shown and described.
